[57] **CLAIM**

The ornamental design for a container interior, as shown and described.

DESCRIPTION

FIG. 1 is a perspective view of a top half of a container interior showing my new design;

FIG. 2 is a perspective view of the bottom half;

FIG. 3 is a plan view of the top half;

FIG. 4 is an enlarged, fragmentary sectional view taken on the line B—B of FIG. 4;

FIG. 5 is an enlarged, fragmentary sectional view taken on line A—A of FIG. 6; and

FIG. 6 is a plan view of the bottom half.

The dash lines in FIGS. 1, 2, 3 and 6 showing the exterior of a container are for the purpose of showing environmental use only.

FIG. I

FIG.2

FIG. 3

FIG. 4

FIG. 5

FIG. 6
